PAPER CARTON

Walter D. Warrick, Chicago, Ill., assignor to The
W. E. Long Company, Chicago, Ill., a corpora-
tion of Illinois

Application June 7, 1937, Serial No. 146,714

6 Claims. (Cl. 229—52)

This invention relates to package holders and more particularly to collapsible containers or receptacles fabricated from cardboard.

One of the objects of the invention is the provision of a new and improved method of constructing and folding sheets of cardboard to form receptacles, package containers or carriers.

Another object of the invention is the provision of a new and improved collapsible paper or fiber receptacle that may be manufactured at a minimum of time and expense and that may be readily and easily assembled without the use of glue or separate fastening members of any kind.

5 A further object of the invention is the provision of a light, inexpensive receptacle, that may be readily collapsed for shipment and easily adjusted for use after shipment or after being collapsed.

10 Other and further objects and advantages of the invention will be apparent from the following description taken in connection with the drawings, in which:

Fig. 1 is a perspective view of the receptacle 15 with the parts folded in position for use;

Fig. 2 is a plan view of the blank from which the receptacle is made;

Fig. 3 is a perspective view of the receptacle with parts only in position for use;

15 Fig. 4 is a section on the line 4—4 of Fig. 1;

Fig. 5 is a perspective view of a modified form of construction, with parts broken away;

Fig. 6 is a plan view of the blank from which the receptacle is made;

20 Fig. 7 is a section on the line 7—7 of Fig. 5; and

Fig. 8 shows the position of the parts when the receptacle is collapsed for shipment.

It is often desirable to leave samples of various products, such as bakery products, or the like, at individual residences for advertising purposes. It is customary, at the present time, to visit the residences for this purpose and call the housewife to the door to receive it or to leave it in a wrapper on the front porch where it may be destroyed or knocked off the porch by children or pet animals and lost entirely until the contents become stale. The present invention seeks to remedy these difficulties by the provision of a package that may be suspended from the doorknob or handle where it is sure to be noticed the first time the door is opened. The receptacle used must, of course, be inexpensive, but, at the same time, it should be neat and attractive. In the present invention, the receptacle

is made from any suitable material such as cellulose acetate, viscose, paper cardboard, or the like.

Referring now to the drawings, the reference character 10 designates the receptacle which is preferably made from cardboard or other fibrous material.

Referring now to Fig. 2, the blank 11 is shown stamped and ready to be folded to form the receptacle. The blank 11 comprises the body portion 12 and the extension 13. The extension 13 is scored along the lines 14 and 15 to form the bottom wall 16 of the receptacle. The extension 13 forms one of the side walls and the body portion 12 is scored at 17 and 18 to form a side wall 19 of the receptacle.

15 The body portion 12 is also scored at 21 and 22 to form the end walls 23 and 24, respectively. The scoring along the lines 21 and 22 also forms the auxiliary side wall sections 25 and 26.

The side section 25 is provided with a slot 27 opening upwardly, as shown in Fig. 2, which forms a tongue member 28, the upper end of which is removed, as clearly shown in Fig. 2. The auxiliary side wall section 26 is provided with a corresponding slot 29 opening downwardly, and when the body portion is folded along the lines 17 and 18, 21 and 22, the slots 27 and 29 are caused to interengage to hold the parts in folded position.

30 The side wall 13 is provided with laterally extending tabs 31, 32, which may be curved on their outer side. These tabs are separated from the body portion by slits 33 and 34, which terminate at the scoring 17 and 18. These extensions are scored along the line 35 and 36, whereby the tabs may be folded at right-angles to the side wall 13 and engage within the end walls 23, 24, when the blank is folded into a receptacle.

35 The end walls 23, 24, may also be provided with extensions or tabs 37, 38, which are scored at their base along the lines 39 and 41, whereby they may be folded at right-angles to extend inwardly from the end walls when the blank is folded to form the receptacle.

The auxiliary side wall sections 25, 26, have 40 extensions 42, 43, which in turn are scored along the lines 44, 45, 46 and 47, respectively, so that they may be folded along the lines to form the top wall sections 48, 49, and the tab sections 51, 52, respectively.

45 The tab sections 51, 52, are adapted to extend downwardly along the inner side of the opposite side wall 19, when the body portion is folded to form the receptacle.

The side wall 13 is adapted to be folded along- 50

55

side the auxiliary side wall sections 25, 26. The side walls 13 and 19 are provided with extensions 53, 54, having the openings 55, 56, for forming handles for carrying the receptacle. If desired 5 the extensions 53, 54, may be provided with slots 40 and 50, whereby the receptacle may be more readily attached to door knobs without making the size of the openings 55, 56, large enough to receive the knobs.

10 In making a receptacle from the blank shown in Fig. 2, the parts are folded at right-angles along the different scoring lines, except the top portions, the slots 27, 29, are caused to engage, and the side wall 13 is folded against the auxiliary side wall sections 25, 26. After the receptacle has been filled the top walls are folded to position.

In Figs. 5 to 8 is shown a modified form of construction, wherein the blank is stamped to 20 form the body portion 57 (see Fig. 6), which is scored along the lines 58, 59, to form one of the end walls 61 of the receptacle, and is scored along the lines 62, 63, to form the end sections 64, 65, of the receptacle. The end sections 64, 25 65, are adapted to be secured together by suitable adhesive 66, as shown in Fig. 5, to form an end wall 60.

The end wall 61 is extended upwardly to form a flap 67, having a notch 68 therein. This flap 30 is scored along the line 69. The end section 64 is also extended to form a top section 71, having a notch 72 therein, and is scored at 73 whereby the same may be bent at right-angles to end section 64. When the parts are assembled the notches 35 68 and 72 are adapted to interlock to hold the top wall sections 67, 71, in interlocked engagement.

The scoring along the lines 58 and 62 forms one of the side walls 74, and the scorings 59 and 63 form the other side wall 75. The side wall 74 40 is scored along its lower portion, as at 76, to form the bottom wall section 77, which has a tongue member 78 extending outwardly therefrom.

The side wall 75 is likewise provided with a 45 bottom wall extension 79, which is provided with a pair of angular slits 81, 82, which are adapted to receive the curved tabs 83, 84, respectively, of the tongue member 78.

The end wall 61 is provided with a downward 50 extension or tab 85, which is separated from the bottom wall sections 77 and 79 by slits 86, 87. The extension 85 is scored along the line 88, so that it may be folded inward above the bottom wall sections.

55 The end section 64 is also provided with an extension or tab 89, which is separated from the bottom wall section 77 by a slit 91. This section is scored along the line 92, whereby it may be folded inward above the bottom wall sections 60 for those sections are interlocked.

The side walls 74, 75, are provided with upward extensions 93, 94, which are provided with openings 95, 96, for forming the handles for carrying the receptacle. In forming the opening 96 65 in the extension of the side wall 75, the extension is slitted along the line 97 to form a flap or tongue 98, which is scored along the lines 99 and 101. The flap 98 is adapted to be folded downward over the top wall sections 67, 71, with its outer end extending downward along the opposite side wall, and is shown more clearly in Fig. 7.

In both forms of construction the receptacle 75 may be collapsed by unfolding the top and bottom walls and moving one of the side walls lat-

erally relative to the other. The collapsed position of the receptacle shown in Figs. 5 to 8 is shown in Fig. 8. If desired, however, the form of the receptacle shown in Fig. 1 may be entirely unfolded to form a flat sheet or plate for shipment, as shown in Fig. 2.

While the receptacle is especially designed for containing sample articles, such as bakery products and the like, it is understood that this use is by way of example only and that the receptacle is capable of numerous uses for commercial purposes, and for other conveniences.

It is thought from the foregoing, taken in connection with the accompanying drawings, that the construction and operation of my device will 15 be apparent to those skilled in the art, and that minor changes in size, shape, proportion and details of construction may be made without departing from the spirit and scope of the appended claims.

I claim as my invention:

1. A collapsible box comprising a bottom wall having an integral tab at each end thereof, end walls, a main side wall integral with the end walls and with the bottom wall, a sectional side 25 wall integral with said end walls, an interlocking connection between the sections of said sectional wall, and a main second side wall integral with the bottom wall, said main side walls having upward extensions forming handle members for 30 carrying said box.

2. A collapsible box comprising a bottom wall, a main side wall integral with the bottom wall, end walls integral with said side wall, a sectional side wall integral with the end walls, and an auxiliary side wall integral with the bottom wall 35 and extending alongside said sectional side wall, said main and auxiliary side walls having their upper ends extending above the box and provided with aligned openings constituting handles for 40 said box, said handles being slotted to facilitate the attachment thereof to the shank of a door knob.

3. A collapsible receptacle made from a single sheet of material, comprising a side wall having 45 its upper end extended to form a handle, a bottom wall integral with said side wall, end walls integral with said side wall, a side wall composed of sections integral with said end walls, said sections having an interlocking connection and a 50 side wall integral with said bottom wall and extending upwardly alongside said sectional wall and provided with a handle extension opposite said first-named handle.

4. A collapsible receptacle comprising a side 55 and a bottom wall integrally connected together, end walls integral with said side wall and having side wall sections integral therewith, said sections having slotted interlocking connections, a second side wall extending upwardly alongside and in 60 contact with said side wall sections and constituting a continuation of said integrally connected side and bottom walls, said side walls having apertured extensions forming handles for carrying said receptacle.

5. A collapsible receptacle comprising integral top, bottom, end and main side walls, said main side walls being integral with said bottom wall, a sectional side wall integral with said end walls 70 and top wall, an interlocking connection between the sections of said sectional side wall for holding said end walls and certain of said side walls in the form of a parallelepiped, and handles extending upwardly from said main side walls.

6. A collapsible receptacle in the form of a 75

parallelepiped made from a single sheet of material comprising vertical side and end walls, and horizontal top and bottom walls, integrally connected together, one of said side walls having an 5 end wall connected to each side thereof along its vertical edges and integral therewith, at least one of said walls being in sections and integral with said sheet, means including interlocking connections integral with said sheet for locking the sections together, an integral portion of each of two 10 side walls of said sheet extending from end wall to end wall above said top wall in the plane of the

respective sides of the receptacle in parallel spaced relation to each other and provided with openings therethrough to form handles for said receptacle, at least one side wall having a fold line defining the top of the receptacle, and an 5 extension integrally projecting beyond said fold line across the top portion of said receptacle and having its free end extending downwardly along the opposite side wall on the inner side thereof for holding said extension in position across the 10 top of said receptacle.

WALTER D. WARRICK.

CERTIFICATE OF CORRECTION.

Patent No. 2,225,492.

December 17, 1940.

WALTER D. WARRICK.

It is hereby certified that error appears in the printed specification of the above numbered patent requiring correction as follows: Page 2, second column, line 28, claim 1, for the words "main second" read --second main--; and that the said Letters Patent should be read with this correction therein that the same may conform to the record of the case in the Patent Office.

Signed and sealed this 21st day of January, A. D. 1941.

Henry Van Arsdale,

Acting Commissioner of Patents.
